ELECTRON DISCHARGE APPARATUS

John Heaver Fremlin, London, England, assignor
to International Standard Electric Corpora-
tion, New York, N. Y.

Application November 27, 1940, Serial No. 367,400
In Great Britain December 22, 1939

6 Claims. (Cl. 250—36)

This invention relates to high frequency electron discharge apparatus of the kind wherein electrons are caused to oscillate about a positive electrode.

The apparatus of the invention comprises means for directing an electron beam over a finite path the potential distribution along which is substantially parabolic so that the field acting upon the electrons at any point in said path is directly proportional to the spacing of that point from a fixed intermediate point in the path about which fixed point the electrons are to oscillate.

Further features of the invention and the advantages derived by the use of the invention will become clear in the following description of certain embodiments given with reference to the accompanying drawing, in which

Figs. 1, 1a, 1b, 2, 3 and 4 are greatly enlarged cross-sectional views of vacuum tube elements in accordance with the invention.

The structure of Fig. 1 comprises a cathode C with a control grid G, anode A and anti-cathode L. The figure is a cross-section of the actual structure which consists of a series of parallel rods extended in a direction perpendicular to the paper.

Now it will be seen that if the electrodes G and L are normally at cathode potential and the anode rods have a considerable positive potential, electrons from the cathode which pass between the rods G will tend to move across the gap towards the anti-cathode L. In a preferred embodiment means are provided for setting up a magnetic field along a line cl running from a point c on the surface of cathode C to a point on the surface of anti-cathode L and through the centers of these elements. This magnetic field is used to ensure that the electrons do not leave the straight path cl. The shape and position of the various electrodes in the tube are so arranged that the potential distribution along the line gl is as far as possible parabolic in form g being the point on line cl determined by the intersection with line cl of a line passing through the centers of grid elements G. This being the case, the field acting upon an electron at any point will be directly proportional to its distance from the point O, this point being approximately midway between g and l. It is assumed throughout that the potentials of G and L are nearly cathode potential. The indicated potentials of A, C, G and L may be maintained by appropriate connections to a source of potential such as battery B.

Now, it is clear that in this circumstance an electron in the space g to l will experience a force which is proportional to its distance from O and is always directed towards O, i. e., the electron will be naturally urged in generally simple harmonic motion about O, and this motion will be accurately synchronous, even though it may gain or lose energy during the period of oscillation about O.

The form of potential distribution described necessitates the use of a magnetic concentrat-
10 ing field for the working of the valve. (Pole-
pieces M indicate diagrammatically a means for
producing a magnetic field.) This appears from
the fact that if the potential distribution along
gl is parabolic with a potential maximum at O,
from Laplace's equation it follows that a little
way off the line gl there must be a field away
from the line gl which would tend, if any electron
deviates from the centre line, to drive it further
away still from that line. No possible arrange-
ment of electrodes could in itself prevent this
phenomenon if a parabolic potential distribu-
15 tion is to be taken on the centre line.

In Fig. 1 the parabolic field distribution along
20 the line gl is attained by making the anode rods
of large diameter preferably greater than their
spacing and comparable with the dimensions Ol,
Og, the grid and anti-cathode rods being of rel-
atively small diameter. If the anode rod diam-
eter is reduced and the distance between cen-
tres remains unchanged the anode potential has
25 to be increased. The precise relation between
dimensions and potentials can be found by
means of a rubber sheet model, probes corre-
sponding to the electrodes being adjusted
30 against opposite sides of the sheet until the sheet
conforms to a parabolic template placed along
the axis of symmetry of the probes.

The new requirements are compared with the
usual conditions in Barkhausen Kurz oscillators
in Figs. 1a and 1b. In Fig. 1a the equipotential
35 lines (dotted) and the corresponding parabolic
voltage curve (chain line) are shown for the
structure of Fig. 1, while Fig. 1b shows the
potentials in the case of a plane cathode Cl, pos-
itive mesh grid Gl and plane anti-cathode L2.

The mode of action of the tube of Fig. 1 is as
follows:

Imagine a continuous emission of electrons
40 from the cathode C between the two wires of the
grid G. These electrons will normally travel
across to L where some of them will be collected
45 and the rest will be reflected back towards the
cathode. Now suppose that the electrode L is

oscillating at the same frequency as the normal frequency of the electrons in the space G to L , the normal frequency being that generally simple harmonic motion due to the parabolic voltage distribution. In this case we shall no longer have a constant proportion of electrons collected by L . The electrons passing O as the electrode L begins to go positive with respect to its normal potential will gain energy from the oscillation and a higher proportion than usual will be collected by the electrode L . These electrons therefore will be removed permanently from the number of electrons oscillating in the space gl . On the other hand, electrons which pass O as the electrode L begins to go negative with respect to its normal potential will lose energy to the oscillation, and in consequence a larger number of them than usual will be reflected and fewer will be collected by the electrode L .

Of the continuous motion of electrons from the cathode C more of these electrons which are moving in such a phase as to give energy to the oscillation are preserved than there are of electrons moving in such a phase as to absorb energy from the oscillation. In consequence of this, the oscillation on balance gains energy from the electron beam, and will build itself up further.

The output may be taken from the anti-cathode rod L and one of the other electrodes for example by extending the rods to form a tuned Lecher wire system.

The structure may be made symmetrical as shown in Fig. 4 by providing additional rods G^1 , A^1 , L^1 similar to those shown in Fig. 1 on the opposite side of the cathode and similarly connected to potential source B . There are, then, two oscillating electrodes, L and a second L^1 symmetrically disposed with respect to the capacities of the rest of the valve, and these two electrodes may be used as output electrodes. They may be sealed straight from the top of the closed bulb in which the valve is built and tuned directly as a pair of Lecher wires to any desired frequency.

In such case it is found that when this external Lecher wire system is tuned to suitable wavelengths, the valve itself begins to oscillate. The frequency of oscillation is found to coincide very well with the calculated frequency of oscillation of the electrons in the space gl , thus showing that the valve is operating in the expected manner. The frequency of oscillation depends first upon the linear dimensions of the valve, and secondly upon the potential of the accelerating electrodes A . It is possible, then, with a good valve, by varying the potential of A , to obtain oscillations of a wide range of wave lengths. This gives the valve a marked advantage over the valves of the Barkhausen type, in which the frequency range is very much limited. It is quite possible to obtain oscillations with potentials between 100 volts and 1000 volts on the electrodes A , which gives us a variation of frequency by a factor greater than 3. It is also possible in some special circumstances to obtain waves of this type in which apparently the oscillation of the Lecher wire system has a frequency double that of the electrons in the space gl . This would extend the frequency range of the valve still further.

It is not proposed that this valve should be used for the production of high powers. Its construction, with thin metal rods, and its necessarily small size preclude the possibility that very high powers can be distributed safely. Its wide frequency range, however, makes it suitable

for use for example as a receiving valve. In one suitable receiving arrangement, it is proposed to work super-regeneratively, using a quenching oscillation at about 5 megacycles, which can best be put on the grid of the valve. It has been found that if the grid potential is changed considerably from the optimum for oscillations, the oscillations are suppressed. If, then, superimposed upon the direct grid potential, we have an oscillation of frequency some 200-300 times smaller than the frequency of the valve, itself, there will be only certain periods during this relatively low frequency oscillation when the valve is in a position to oscillate.

If a received signal is now impressed upon the Lecher system the valve will break into oscillation much more rapidly than if there is no such signal and the start of oscillation has to depend entirely upon random thermal variations. In consequence, if a signal is being received the valve will be oscillating on the average for a greater proportion of its time than would be the case if no signal exists. The oscillation of the valve can be detected by measuring the direct current to the Lecher wire systems. It is clear that with the mode of oscillation which occurs, the number of electrons arriving at L will be considerably affected by the existence of oscillations. Consequently, either a sensitive meter or telephones in the circuit of L will register changes in the current to L in a way suitable either for direct detection or for further amplification. The valve in fact when used as a super-regenerative receiver acts also as its own detector.

A number of further variations within the scope of the invention will now be referred to.

Instead of making the system of Fig. 1 as nearly as possible symmetrical about the point O so as to give a single uniform parabola in the field distribution, we may construct the valve in such a way that the length Ol is one-third of the length Og as shown in Fig. 2. The electrode structure is so arranged then that instead of having a single parabolic potential distribution between g and l we have now two different parabolic distributions, one between O and l and the other between O and g . In order to effect this, it is necessary that the two anode rods A should be very close together, to ensure that the spaces on either side of these rods should be well shielded from one another. In this case, the mode of phase selection of the electrons at the Lecher wire anti-cathode L is unchanged, and an electron, instead of crossing from O to G and back to O again in half the period of the oscillation of the Lecher wire, now does it in $1\frac{1}{2}$ periods of the oscillation of the Lecher wire. It then returns in the same phase as it would have if the distance O to G were still identical with the distance O to L . This has, however, the mechanical advantage that the space O to G can be made considerably larger for a given desired wave length without making it necessary for the anode potential to be excessively high. Valves of this lop-sided type oscillate satisfactorily down to wave lengths of 10 cm. at anode potentials not greater than 400 to 500 volts.

A drawback which has been found in constructing the valves with electrodes arranged symmetrically about the cathode lies in the fact that it is very difficult mechanically to construct the two sides of the valve accurately alike. Small differences between the two sides lead to the production of oscillations in two different wave lengths for the same potential on the anode rods.

These do not, of course, co-exist at any one time, but each can be obtained by tuning the Lecher wire system suitably. This lack of symmetry is often inconvenient as the peaks of current of the Lecher wires, as the external circuit is tuned, often over-lap. This has been avoided by coating one side of the cathode only (in any case, the cathode is normally coated only in narrow strips opposite to the gap between the grid wires G). The necessity for constructing both sides of the valve and then using one side only is however a disadvantage and it is best to revert to the single sides structure of Fig. 1 in which the pair of electrodes which are being continued outside the valve as a tuned Lecher wire circuit consist of the grid and electrode L. This also takes up less space, which is important when it is remembered that the magnetic field is essential to the working of the valve. With overall dimensions of the order of 1 cm. or less small permanent magnets as indicated by reference characters M can be used and an adequate field still obtained. The working length of the electrode system, that is the length of each rod electrode may be about 2 cm.

It is also proposed to construct the whole tube in metal such as copper, e. g., as shown in Fig. 3. In this figure the parabolic field distribution is set up inherently because of the shape of the conductive envelope. This envelope is shown to comprise two generally cylindrical portions F and H, joined by two preferably integral longitudinally extending reentrant portions X. The metal envelope is given a positive potential, and the two points X thus correspond to the anode rods of Fig. 1, as far as function is concerned. It is then possible for the electrode L to be tuned as the centre of a concentric line, the surrounding envelope being tuned as the outside of this line. It would be possible of course to have two cathode and control grid systems, each as shown in Fig. 3, opening off the concentric line on opposite sides. It would thus be possible to obtain oscillations of greater amplitude from the system. Since, however, the tube is primarily for use as a receiver, it is probably not convenient or particularly advantageous to do this, as it increases the complication of the construction, and it is easier rather to amplify the signal after detection than to produce a high amplitude initially.

What is claimed is:

1. Electron discharge apparatus including a cathode, a pair of grid members each spaced equally from said cathode and spaced from each other, a pair of accelerating electrode members each spaced equally from said cathode and spaced from each other, the spacing from one of said grid members to one of said accelerating electrode members being equal to the spacing of the other of said grid members from the other of said

accelerating electrode members, an anti-cathode member spaced equally from each of said accelerating electrode members, and means producing a magnetic field extending from said cathode to said anti-cathode and generally perpendicular to all said members.

2. Electron discharge apparatus including a cathode, a pair of grid members each spaced equally from said cathode and spaced from each other, a pair of accelerating electrode members each spaced equally from said cathode and spaced from each other, the spacing from one of said grid members to one of said accelerating electrode members being equal to the spacing of the other of said grid members from the other of said accelerating electrode members, an anti-cathode member spaced equally from each of said accelerating electrode members, means producing a magnetic field extending from said cathode to said anti-cathode and generally perpendicular to all of said members, a pair of Lecher wires, one of said Lecher wires being connected to said anti-cathode, and the other of said Lecher wires being connected to another electrode of said tube.

25 3. Electron discharge device comprising a generally cylindrical cathode member, a plurality of pairs of grid members each spaced equally from said cathode member, said members of said pairs being spaced from each other, a corresponding plurality of pairs of accelerating electrode members, in each of said corresponding pairs the spacing from one of said accelerating electrode members to one of said grid members being equal to the spacing of the other of said accelerating 35 electrode members from the other of said grid members, and a plurality of anti-cathode members corresponding to said plurality of pairs of grid members and accelerating electrode members, each of said anti-cathode members corresponding to a pair of said accelerating electrode 40 members being spaced equally from each of said last-mentioned accelerating electrode members.

4. Electron discharge apparatus according to claim 1, in which said cathode and said members are each generally cylindrically shaped and disposed in their respective axial directions parallel to one another.

5. Electron discharge apparatus according to claim 1 wherein said cathode and said grid members are enclosed in an envelope of conducting material, and wherein said pair of accelerating electrode members are formed by two parallel oppositely disposed reentrant portions formed in said envelope.

55 6. An electron discharge device according to claim 2 wherein one of said Lecher wires is connected to said anti-cathode and the other to said grid members.

JOHN HEAVER FREMLIN.
